ALBERT BROWN, OF ROCHESTER, NEW YORK, ASSIGNOR TO VOGT MANUFACTURING CORPORATION, OF ROCHESTER, NEW YORK, A CORPORATION OF NEW YORK

PULL CORD OR THE LIKE AND METHOD OF MAKING THE SAME

Application filed July 1, 1929. Serial No. 375,106.

My present invention relates to cordage and more particularly to pull cords or "assist grips", as they are called, of the nature used, for instance, in the interior fittings of automobile bodies to provide grips whereby passengers may steady themselves in their seats, and the invention has for its object to provide a decorative and yet strong and durable pull cord of this character. The improvements are directly more particularly toward the provision of means whereby the cord will hold its shape and position to better advantage than hitherto and toward the method of making it.

To these and other ends the invention resides in certain improvements and combinations of parts, all as will be hereinafter more fully described, the novel features being pointed out in the claims at the end of the specification.

In the drawings:

Fig. 1 is a front view of a pull cord or assist grip fitting for automobiles constructed in accordance with and illustrating one embodiment of my invention;

Fig. 2 is a similar view of the cord with the top portion thereof partly broken away as well as the center and the rest in longitudinal central section;

Fig. 3 is a fragmentary detail of the attached end of the cord with the stocking or outer covering removed;

Fig. 4 is a transverse section through the body of the cord, and

Fig. 5 is a view similar to Fig. 1 on a reduced scale illustrative of the manner in which the spring core is inserted.

Similar reference numerals throughout the several views indicate the same parts.

A pull cord of the kind mentioned and as shown in Fig. 1 comprises an attaching plate A having a ring portion B secured in sliding engagement with a shank portion or body cord C. At the lower end of the latter is a tassel C which, in connection with a collar E surrounding the cord constitutes the hand grip that is grasped by the passenger. The manner in which I prefer to assemble these elements in general and to secure them together is disclosed and claimed in prior pend-

ing application Serial No. 328,249, filed December 24, 1928, and need not be described in any great detail herein. The body member or intermediate portion C of the cord is in the form of a twisted rope composed of strands 1, there being four strands in the present embodiment. These are tightly held together at their upper ends against untwisting preferably in the operation of securing the upper end of the cord to the ring B. As shown more in detail in Fig. 3, the upper ends may be ravelled, doubled over the ring so that they are turned back upon the body and encircled by a ring 2, such as a wire suitably twisted and fastened thereabout.

The lower end of the cord is similarly fastened against untwisting by a wire 3, with which is interlocked a wire 4 that holds the pompon together and in place. A preferably wooden sleeve 5 is drawn down over the connection to conceal it, as illustrated in Fig. 1, being covered with a stocking 6, while at the top a stocking 7 may be used to conceal the fastening device at that end first described.

Heretofore these pull cords or assist grips have usually been made wholly flexible as to the body portion C and as they are commonly composed of silk or other fine threads, they become limp, stretched and distorted in use having a tendency to kink. Besides, the former constructions were very light and not so easy to find with the hand and grasp. In the practice of my present invention, I provide the body portion C with a resilient, bendable core which holds it straight and relatively stiff when not in use, but yields gently to the grip of the hand when in use. I prefer to constitute this core of a small, tightly coiled, helical, steel spring of the nature shown at 8 in Figs. 2 and 5. It is somewhat shorter than the cord body C, as shown, and has a free or floating position therein, being unattached at either end so that it may slide longitudinally with its flexing movements.

In effect, it appears that the strands 1 of the rope body C are twisted about the spring core 8, but in my preferred method of manufacture I completely form the rest of the pull cord or assist grip before adding the spring.

That is, the end fastenings 2 and 3 are applied and the attacher and grip elements also preferably completed, after which I forcibly locally untwist or spread the strands 1 at one 5 end, inserting the end of the spring core 8 therein, and thereafter further progressively spread the strands down the length of the body with a revolving motion of the cord while at the same time progressively tucking 10 the spring between the strands, as illustrated in Fig. 5. The strands enfold it completely without any permanent distortion of themselves so that the spring occupies the exact center of the cord, as shown in Fig. 4. Thus 15 the floating character of the spring not only promotes its proper functioning in use but makes possible this very simple and convenient mode of attaching it.

The spring core really has the effect of 20 tightening the twist of the strands so that the cord as such holds its shape better than the core and the added weight of the spring causes it to hang gracefully and offer an altogether more substantial grip.

25 I claim as my invention:

1. An assist grip comprising a body portion of coiled flexible material, attaching means at one end thereof, a grip at the other end thereof, and a resilient member positioned within the coils of said body portion and free to move longitudinally with respect thereto.
2. An assist grip comprising a flexible body portion, attaching means at one end thereof, a grip at the other end thereof, and a spring within said flexible member and with its respective ends free to move longitudinally with respect to said attaching means and said grip.
3. An assist grip comprising a plurality of twisted cords forming a body portion, attaching means at one end thereof, a grip at the other end thereof, and a spring concealed and surrounded by said twisted cords and capable of endwise movement relatively thereto.
4. In an assist grip, the combination with a flexibly inert rope-like body portion composed of twisted rope strands, of an attaching device secured to one end thereof, a gripping element secured to the other end thereof, and a closely coiled spring extending centrally through the body portion and completely covered thereby.
5. In an assist grip, the combination with a flexibly inert rope-like body portion composed of twisted rope strands, of an attaching device secured to one end thereof, a gripping element secured to the other end thereof, and a closely coiled spring extending centrally through the body portion and completely covered thereby, said spring being otherwise unattached and free to move longitudinally.
6. A method of making assist grips of the

character described which embodies first preparing a twisted strand rope-like body portion, securing the ends thereof against untwisting by means of the attaching and grip elements, respectively, and then inserting a 70 spring core in the center of the rope body so that it is completely covered thereby by spreading the strands at one end, inserting one end of the spring and further progressively spreading the strands down the length 75 of the body while progressively tucking the spring between them.
